COMBINED LAWN EDGER AND TRIMMER

Robert O. Ernest, Oak Park, and Ross E. Cornwell, Chicago, Ill., assignors to Sunbeam Corporation, Chicago, Ill., a corporation of Illinois

Filed May 29, 1963, Ser. No. 75,122

Term of patent 14 years

(Cl. D40—1)

FIGURE 1 is a perspective view of a combined lawn edger and trimmer embodying our new design;

FIG. 2 is an enlarged left side elevation thereof, with the handle fragmentarily shown for ease of illustration;

FIG. 3 is a front elevation thereof with the handle omitted for ease of illustration;

FIG. 4 is a top plan view, thereof, as shown in FIG. 2;

FIG. 5 is an enlarged right side elevation thereof, as shown in FIG. 2; and

FIG. 6 is a rear elevation thereof, as shown in FIG. 2.

We claim:

The ornamental design for a combined lawn edger and trimmer, as shown.
